[57] CLAIM

The ornamental design for a water bottle holder, as shown and described.

DESCRIPTION

FIG. 1 is a pictorial view of a water bottle holder showing my new design;

FIG. 2 is a front-elevational view thereof;

FIG. 3 is a right side-elevational view thereof;

FIG. 4 is a rear-elevational view thereof; and,

FIG. 5 is a left side-elevational view thereof.

FIGS. 2, 3, 4 and 5 include phantom lines of a bottle which are for illustrative purposes only and are not part of the claimed design.
